UNITED STATES PATENT OFFICE.

THOMAS J. CORNING, OF SAN JOSÉ, CALIFORNIA.

BALING-PRESS.

SPECIFICATION forming part of Letters Patent No. 403,738, dated May 21, 1889.

Application filed January 29, 1889. Serial No. 298,016. (No model.)

To all whom it may concern:

Be it known that I, THOMAS J. CORNING, a citizen of the United States, residing at San José, in the county of Santa Clara and State 5 of California, have invented a certain new and useful Improvement in Baling-Presses, of which the following is a specification.

This invention consists of certain new and useful features of construction and combinations of parts, hereinafter described, and pointed out in the claims.

This invention also involves mechanism for actuating the plunger and feeding the material to be baled into the press.

Referring to the accompanying drawings, which form a part of this specification, Figure 1 is a longitudinal vertical partial section of the press through the dotted lines $x\ x$ of Fig. 3. Fig. 2 is an enlarged detail view of the 15 press shown in Fig. 1. Fig. 3 is a longitudinal horizontal partial section of the same through the dotted line $x'\ x'$ of Fig. 1. Fig. 4 is an end view of the press. Fig. 5 is a plan view of the central portion of the same. Fig. 20 6 is a horizontal section of the plunger through the dotted line $x^2\ x^2$ of Fig. 2. Fig. 7 is a detail view of double cranks and shaft for driving the press-feeder. Fig. 8 is a detail view of double cranks, shaft, dog, and 25 arms for operating a folder, to be described 30 hereinafter.

Like letters of reference indicate corresponding parts throughout the several views.

A represents the main frame of the press, 35 which is rectangular in form and consists, essentially, of the side pieces, A', cross-pieces A², and posts a A³, all of which parts are firmly secured together. The frame A is provided with a floor, A⁴, whereon the plunger slides to 40 form bales and along which the latter are driven to discharge them from the press. The upper side of the frame is partially inclosed by means of boards A⁵. The central portion of the frame is provided with side boards B, 45 to which are secured uprights B', through which horizontal rods B² pass, the latter having thumb-nuts B⁶ applied to their ends, which are threaded. The end portion of the frame is also provided with side boards B³, to which 50 are secured uprights B⁴, through which are passed horizontal rods B⁵, having thumb-nuts B⁶ applied to their ends, which are threaded.

The lateral diameter of the portions of the press included between the side boards, B B³, may be diminished, as indicated by dotted 55 lines, by turning the thumb-nuts B⁶.

For convenience in referring thereto the central portion of the press will be designated as the "baling-chamber" and the right-hand end portion as the "compression-chamber." 60

E is a gear-wheel mounted on the horizontal shaft E', which is provided with bearings E².

E³ E⁴ are horizontal bearing-pins projecting from the opposite sides of the wheel E, 65 one pair of said pins, as E³, being located preferably twice the distance from the shaft E' that the pins E⁴ are.

F represents guide-bars, the functions of which will be described hereinafter, connected with the press, preferably by means of upright portions F'.

G is a reciprocating plunger, which is in form a quadrangular box minus one end.

G' is a hinge-plate provided with lugs G² 75 and attached to the inside of the end of the plunger.

G³ is a longitudinal slot in the lower portion of the plunger G.

H is a bifurcated pitman jointed by one end 80 thereof to the lugs G² of the hinge-plate G'.

The bifurcation H' of the pitman H adapts the latter to slide nearly its entire length astride the gear-wheel E. The pitman H is provided with notches H² H³ on the under 85 side thereof to adapt the same to engage with the bearing-pins E³ E⁴, whereby power is transmitted from the gear-wheel E through the pitman to the plunger.

H⁴ represents guide-pins projecting transversely from the outside of the free end of the pitman sufficiently to allow the same to engage with the guide-bars F, whereon they are adapted to slide, and whereby the pitman is disengaged from the pins E³ E⁴ after each 95 operative stroke of the plunger.

I represents helical springs—a preferable form—attached to the plunger G in any suitable manner, and provided at their free ends with eyes I'.

I² represents connecting-rods having one pair of their ends jointed to the eyes I' of the spring I and their other ends passed through openings in the upright portions F' of the 100

guide-bars F, wherein they freely slide, as indicated by dotted lines, and wherefrom they are prevented from escaping by means of nuts I³.

5 J is a horizontal rock-shaft having double cranks J' rigidly connected with the ends thereof.

J² is a dog, also rigidly attached, preferably, to the central portion of the same. The shaft 10 J passes through the bottom of the baling-chamber of the press.

J³ is a folder mounted by means of the arms J⁴ upon the top of the press, whereto they are attached by means of hinge-joints J⁵.

15 J⁶ are connecting-rods connecting the folder J³ through the arms J⁴ with the free ends of the double cranks J', whereby said folder is operated.

J⁷ are forks attached to the back side of the 20 folder J³, and their office will be more fully described hereinafter.

K is a shaft having double cranks K' rigidly connected therewith.

K² are axes projecting transversely outward from the free ends of the cranks K', whereto they are also rigidly connected. The axes K² are mounted horizontally in the posts a, between which the cranks K' are revolute.

30 L is a longitudinally-reciprocating feeder provided with downwardly-curved teeth L', projecting from the under side thereof, for conveying material to be baled into the spout of the press. The upper end of the feeder L is mounted upon the shaft K, whereon it revolves when in operation. The lower end of the feeder L is supported and guided by means of pintles L², projecting from the edges thereof into the grooved ways L³ in the side 35 pieces, L⁴.

The lower end of the feeder L is provided with longitudinal slots L⁵ to admit the passage of the forks J⁷ therethrough, for a purpose to be described hereinafter. The parts L L⁴ L⁶ serve to form a spout, L⁷, for 45 conveying material from the hopper L⁸ into the baling-chamber of the press.

M is a gear-wheel meshing with the gear-wheel E, mounted on the horizontal shaft M', which is provided with bearings M².

50 M³ is a sprocket-wheel mounted on the shaft M'. M⁴ is a driving-pulley, also mounted on the same shaft.

K³ is a sprocket-wheel mounted on the outer end of one of the axes K².

55 K⁴ is a chain belt connecting the sprocket-wheels M³ K³, and serves to transmit power from the sprocket-wheel M³ to the shaft K, which drives the feeder L.

To operate the press I proceed as follows:

60 Supposing the plunger and pitman to be in the positions indicated by the dotted lines y in Fig. 2, the press to be charged in the usual way, and the hopper L⁸ to be filled with hay, apply power to the pulley M⁴, which being 65 transmitted to the feeder L, the latter will convey the hay downward into the spout L⁷, whence it is forced into the baling-chamber

by means of the folder J³ and the forks J⁷. Simultaneously with the operations above described the bearing-pins E³ engage with the notches H³ in the pitman H, which, together with the plunger G, will be driven to the positions indicated by the dotted lines y'. When the pitman and plunger reach the points last indicated and the bearing-pins E³ 70 disengage from the notches H³ and simultaneously with such disengagement the bearing-pins E⁴ engage with the notches H² in the pitman H, the latter will drive the plunger G to the position shown in full lines in Fig. 2. 80 When the plunger and pitman have reached the position shown in full lines in Fig. 2, one charge of the material to form the bale will have been driven into the compression-chamber of the press. Immediately thereafter the bearing-pins E⁴, passing downward, become disengaged from the notches H², and the plunger G and the pitman H are driven by the action of the springs I and the elasticity of the material being baled to the positions 85 indicated by the dotted lines y. A repetition of the simultaneous operations just described will add another charge to the bale. Obviously any number of charges within the limit of the press may be united to form the bale. 90 The folder J³, with its forks J⁷, are raised to the position shown in Fig. 1 by means of the bottom of the plunger passing over and pressing downward the dog J², which operates the shaft J, cranks J', and rods J⁶. Upon the return of the plunger to the position indicated by the dotted lines y, the dog J² is released and enters the slot G³ in the plunger G, and the folder J³, with its forks, descends of its own weight, carrying with it the charge of 95 hay just accumulated in the spout L⁷.

I wish to call particular attention to the manner in which power and motion are transmitted from the bearing-pins E³ E⁴ to the pitman and plunger. By locating the bearing-pins E³ near the periphery of the wheel E, I obtain increased speed for the first two-thirds of the stroke of the plunger, while the material is loose in the press. Afterward the bearing-pins E⁴, being located near the shaft of 110 the wheel E, transmit less motion and double power, as the material becomes more compact, to the finishing of the stroke of the plunger.

It will be found in practice that when the 115 material being baled is dry it will be sufficiently elastic to force the plunger and pitman back to the positions indicated by the dotted lines y, little, if any, assistance being required from the springs I. When the aid 120 of the springs is not required, I prefer to narrow the left-hand end of the baling-chamber by drawing inward the side boards thereof by means of the rods B² and thumb-nuts B⁶ to 125 form a brake for the plunger; but the aid of the springs will be found to be indispensable when the material to be baled is wet.

When it is desired to increase the compactness of bales, diminish the lateral diameter

of the compression-chamber throughout its entire length by means of the side boards B³ and thumb-nuts B⁶.

I claim—

- 5 1. In a baling-press, in combination, the bifurcated pitman having notches therein and guide-pins thereon, the wheel provided with bearing-pins—one of said pins being located near the periphery of the wheel and the other nearer the shaft of the same—projecting from the sides thereof and adapted to engage with the notches in said pitman, and guide-bars for supporting and guiding the free end of the pitman, substantially as described.
- 15 2. In a baling-press, in combination, the bifurcated pitman having notches H² H³ therein and guide-pins H⁴ thereon, a plunger attached to one end thereof, a wheel provided with bearing-pins E³ E⁴, arranged to engage with the notches in said pitman, and guide-bars adapted to support and guide the free end of said pitman, substantially as described, for the purpose set forth.
- 25 3. In combination, the pitman having notches H² H³ therein and guide-pins H⁴ projecting therefrom, a wheel provided with bearing-pins projecting from the side thereof and arranged to engage with the notches in said pitman, guide-bars adapted to receive and
- 30 30 guide the free end of the pitman, and a plunger attached thereto and provided with a

spring for propelling the same backward, after completing the compression-stroke, to the end of the retraction-stroke, substantially as described, and for the purpose specified. 35

4. In a baling-press, in combination, the baling-chamber, a plunger adapted to operate therein, a folder mounted upon the press by means of swinging arms J⁴, having forks J⁷ attached thereto, the rock-shaft J, provided with double cranks J' and dog J², rigidly connected therewith, and connecting-rods J⁶, substantially as described. 40

5. In a baling-press, in combination, the baling-chamber, a plunger adapted to operate 45 therein, a longitudinally-reciprocating feeder, L, provided with downwardly-curved teeth projecting from the under side thereof and mounted upon the shaft K, the latter being supported by double cranks K' and axes K², 50 side pieces, L⁴, and part L⁶, to form a spout, the folder J⁸, mounted upon the press by means of swinging arms J⁴, having forks J⁷ attached thereto, the rock-shaft J, provided with double cranks J' and dog J², rigidly connected therewith, and connecting-rods J⁶, 55 substantially as described.

THOMAS J. CORNING.
